UNITED STATES PATENT OFFICE.

FREDERICK J. MILLER, OF WILMINGTON, DELAWARE, ASSIGNOR TO THE DIAMOND MATCH COMPANY, OF CHICAGO, ILLINOIS.

MATCH-MACHINE.

SPECIFICATION forming part of Letters Patent No. 651,635, dated June 12, 1900.

Application filed December 5, 1898. Serial No. 698,284. (No model.)

To all whom it may concern:

Be it known that I, FREDERICK J. MILLER, of Wilmington, in the county of New Castle, and in the State of Delaware, have invented 5 certain new and useful Improvements in Match-Machines; and I do hereby declare that the following is a full, clear, and exact description thereof, reference being had to the accompanying drawings, in which—

10 Figure 1 is a side elevation of a match-machine in which my improvements are embodied. Fig. 2 is a detail view, in vertical section, of the mechanism for cutting the splints, placing them in the carrier, and for 15 discharging the completed splints from the carrier. Fig. 3 is a view in side elevation of the same portion of the machine that is shown in Fig. 2. Fig. 4 is a plan view thereof, and Fig. 5 is a detail perspective view of a portion of the carrier.

Letters of like name and kind refer to like parts in each of the figures.

The object of my invention is to provide 25 a machine for making matches so as to increase the efficiency thereof, simplify its construction, and avoid the use of parts that require accurate adjustment, and hence are apt to be easily deranged; and to these ends said invention consists in the machine having the 30 features of construction substantially as hereinafter specified.

In the embodiment of my invention as shown in the accompanying drawings wooden splints are used in making the matches and 35 a splint-cutting mechanism is illustrated as a part of the machine; but it is to be understood that this is merely one adaptation of my improvements, as the latter can be employed when the cutting mechanism is not a 40 part of the organized machine and also when paper or waxed threads or tapers are used instead of wood for making the splints.

The splint-cutting mechanism illustrated 45 is mounted in a suitable frame A and consists of a series of bars B and B, each carrying a tubular cutter b, fixed in a vertically-reciprocating head C, that receives motion from a cranked driving-shaft D, as is customary in match-making machines. Said shaft has the 50 usual band-wheel E, belted to a suitable

source of power. The head C carries beneath the cutters B the usual block-trimming knife c.

The blocks of wood from which the splints are cut are fed to the cutters by mechanism like that shown in the Beecher patent, No. 55 389,435, issued September 11, 1888.

As is common in match-machines, I employ an endless or continuous carrier into which the splints are placed and by which they are carried to the heating, paraffining, and composition-applying devices and from which the finished matches are discharged, the said carrier being made to travel above the cutter-carrying head to receive the cut splints as they are carried upward by said head. The 60 carrier I employ consists of an endless chain whose links are each composed of parallel longitudinally-extending bars F and F, the ends of the bars of one link being connected by a transverse rod or bolt G with the ends of the 65 bars of an adjoining link. The end of the bar of one link has at one end at its transverse center a single lug f, that enters between a pair of lugs f' and f' on the connected bar, each bar having at one end the single 70 lug and at the other end the pair of lugs, and of course throughout the chain the bars whose ends are thus connected are in line with each other. The bars have flat sides, being preferably rectangular in cross-section, and adjacent bars are separated from each other by a space less in width than the thickness of a 75 match-splint, such separation being effected and preserved by washers H and H upon the connecting rod or bolt G. Into such space the 80 splints from the cutters or other source of supply are thrust, and preferably for each splint a cavity or seat is provided to hold it firmly and steadily at a right angle to the carrier, that 85 consists of opposite grooves or notches f² and f² in the adjacent sides of adjoining bars. As 90 said splint seat or cavity is slightly smaller in size than the thickness of the splint to insure the latter being held, the end at which the splint enters is flared, as shown, to guide and 95 gradually compress the splint.

For driving or moving the carrier the two outermost bars of each link, and, if desired, one or more intermediate ones, as well, are constructed for coöperation with suitable 100

driving-wheels. Preferably in the two sides of each of the bars that are at right angles to the splint-engaging sides there are regularly-spaced transverse grooves or notches f^3 and f^3 , adapted to be engaged by the teeth of wheels I and I, placed, respectively, on opposite sides of the bar, said wheels being mounted on shafts K and K, suitably journaled on the frame A. The two shafts K and K are geared together to cause them to move in unison, and they are rotated step by step to give intervals of rest in the travel of the carrier to permit the insertion of splints therein. Any desired means for so rotating said shafts may be employed. I show a pawl-and-ratchet mechanism for the purpose, the ratchet-wheel L being mounted on a shaft M and the pawl N, carried by a lever O, that is vibrated by suitable means from the main shaft D—such, for example, as is shown in the patent above referred to. A gear P on the shaft M, meshing with an idler Q, that is also in mesh with the gear on one of the shafts K, transmits the motion of the ratchet-wheel to said shaft K.

As it is likely that splints may be somewhat awry or project different distances from the carrier, it is desirable to provide some straightening or evening device at some point before the splints reach the composition-
plying mechanism. I provide for this purpose a roller or cylinder R, having in its surface cavities or depressions r and r , that have inclined sides to engage any irregularly-placed splints on their ends and straighten and move them to proper position in the carrier. Said cavities are arranged in parallel rows that extend in lines parallel with the axis of the roll which is transverse of the carrier, and the number of cavities in a row is the same as the number of splints in a row running crosswise of the carrier, so that each splint in a row has its own cavity. It is sufficient that the cavity have such shape that it will have inclined sides in a line parallel with the length of the carrier and also in a line extending crosswise thereof, as the splints are apt to incline only in either of these directions, but I prefer to make the cavity round, and hence of conical form, as such shape is easily made and will engage the splint in whatever direction it may incline.

The evener-roll may be conveniently mounted in bearings on the frame A. As thus placed, it may be readily geared to and driven by one of the shafts K, so as to insure its being rotated in unison with the rate of travel of the carrier. The gearing shown comprises a sprocket-wheel S on the shaft K, a sprocket-wheel T on a shaft U, parallel with the roll, a chain V, connecting said wheels, a gear-wheel u on the shaft U, and a gear-wheel r' on the roll-shaft meshing with and receiving motion from said gear u . Preferably on the shaft U there is a smooth roll W to engage the ends of any splints that might possibly be projected too far on the side of the carrier opposite the side at which they are inserted and

to constitute a support for the carrier and splints under the thrust imparted by the engagement of the roll R. After leaving the roll R the splints are carried to drying, paraffining, and composition-applying mechanisms similar to those of the patent before mentioned, and then, as in the machine of said patent, over several drums X and X back to the mechanism on the frame A to give time for the composition to cool and harden before the complete matches are removed from the carrier. Besides the carrier-driving wheels I and I on the frame A other wheels Y and Y engage the carrier and impart to the portion they engage a continuous motion, as in the machine of the patent before referred to, and said wheels are driven in the same way as are the wheels for the like purpose in said machine.

For ejecting or discharging the matches from the carrier I mount on the frame A, upon the shaft M, a series of thin wheels or disks Z and Z, that respectively pass into the spaces between the carrier-bars F and F and engage the ends of the splints between the bars and easily and gently force them downward and out of the carrier. Said disks are notched at suitable points in their peripheries to enable them to pass over the washers applied to the bar-connecting bolts G. By placing the discharging-wheels on the shaft M as the latter is geared to the carrier-moving wheels I and I said discharging-wheels are made to revolve in unison with the rate of travel of the carrier. As portions of the discharging-wheels are always in the spaces between the carrier-bars and as their action is easy and gentle, it is apparent that there is a marked advantage over machines which have punches or ejecting devices which reciprocate into and out of the carrier, whose movements must be accurately timed and adjusted to the movements of the carrier, arrangement of which causes breakage of the machine and which are productive of objectionable jarring and vibration.

Having thus described my invention, what I claim is—

1. A carrier for match-machines, composed of pivotally-connected, longitudinally-extending bars between which splints are held, substantially as and for the purpose described.
2. In a match-machine, the combination of a splint-carrier, composed of longitudinally-extending bars, and driving-wheels for the carrier that co-operate with certain of the bars, substantially as and for the purpose described.
3. The combination of a traveling splint-carrier, and a splint-evener having splint-end engaging and surrounding cavities each of which has its sides converging toward each other and inclining in directions that extend laterally and longitudinally with reference to the line of movement of the carrier, substantially as and for the purpose described.
4. A splint-evener for match-machines, consisting of a roll having conical cavities in its

surface, substantially as and for the purpose described.

5. The combination of a carrier having longitudinally - extending surfaces between which are spaces, and a disk or wheel extending into each of said spaces, substantially as and for the purpose described.

6. The combination of a splint-carrier composed of longitudinally-extending bars arranged side by side with spaces between them,

ejector-wheels extending into such spaces, and gearing for revolving such wheels, substantially as and for the purpose described.

In testimony that I claim the foregoing I have hereunto set my hand this 19th day of 15 November, 1898.

FREDERICK J. MILLER.
